H. F. WAITE,
X-RAY SYSTEM,
APPLICATION FILED OCT. 18, 1917.

1,277,003.

Patented Aug. 27, 1918.

Inventor
Harry F. Waite
By his Attorney
O. E. Edwards

UNITED STATES PATENT OFFICE.

HARRY F. WAITE, OF NEW YORK, N. Y.

X-RAY SYSTEM.

1,277,603.

Specification of Letters Patent. Patented Aug. 27, 1918.

Application filed October 18, 1917. Serial No. 197,201.

To all whom it may concern:

Be it known that I, HARRY F. WAITE, a citizen of the United States, and a resident of Whitestone Landing, county of Queens, city and State of New York, have invented a new and useful Improvement in X-Ray Systems, of which the following is a specification.

The object of my invention is to provide a system of this class for dental and similar work in which rotating parts are eliminated together with all troubles incidental thereto. This and other objects are accomplished by my invention, one embodiment of which is hereinafter more particularly set forth.

For a more particular description of my invention, reference is to be had to the accompanying drawings, forming a part hereof, in which is shown a diagram of my system.

This system 1 is provided with an alternating or similar current from any suitable source, as a generator 2 which sends electricity over the main wires 3 and 4. The wire 3 runs directly to a hot cathode filament 5 in a tube 6 and this filament has a second wire 7 that runs to a coil 8 of the primary 9 of a transformer 10. The wire 3 is also connected to this primary 9, as indicated so that a low voltage current may flow through the hot cathode 5. The wire 3 is also connected to the secondary 11 of the transformer 10 so as to have a suitable connection with the hot cathode 5.

The anode 12 of the tube 6 is connected by a wire 13 with the opposite end of the secondary or high tension winding 11 of this step up transformer 10. The primary 9 of this transformer 10 is also connected to the wire 4.

In view of the foregoing the operation of my improved system will be readily under-

stood. The filament 3 is brought to a proper state of incandescence by electricity taken from a few coils of the primary 9 and then a high tension current passes through the tube 6 from the transformer 10 in one direction only and in the proper direction, that is, from the anode 12 to the cathode 5, as all inverse waves are suppressed by the tube 6 which acts as a valve. This passing of the high tension current through the tube 6, in the conventional manner, generates X-rays which are used as desired.

While I have shown and described one embodiment of my invention, it is obvious that it is not restricted thereto, but is broad enough to cover all structures that come within the scope of the annexed claims.

What I claim is:

1. In a system of the class described, a step-up transformer with a low tension circuit and a high tension circuit, a hot cathode X-ray tube in the high tension circuit, and conductors connecting the hot cathode of the high tension circuit with the low tension circuit.

2. In a system of the class described, a step-up transformer with a low tension circuit and a high tension circuit, an X-ray tube in the high tension circuit with a hot cathode and means for heating this cathode with currents in the low tension circuit.

3. In a system of the class described, a step-up transformer with a low tension circuit and a high tension circuit, an X-ray tube in the high tension circuit, provided with a hot cathode, and means for supplying this hot cathode with electricity from a few coils of the primary of this transformer.

In testimony whereof I have placed my hand this 16th day of October, 1917.

HARRY F. WAITE.
